UNITED STATES PATENT OFFICE.

GROVER C. HAUSER AND JOHN H. DOLAN, OF ROCHESTER, NEW YORK.

FOOTWEAR.

1,261,524.

Specification of Letters Patent.

Patented Apr. 2, 1918.

Application, filed September 8, 1917. Serial No. 190,410.

To all whom it may concern:

Be it known that we, GROVER C. HAUSER and JOHN H. DOLAN, citizens of the United States, and residents of Rochester, in the 5 county of Monroe and State of New York, have invented certain new and useful Improvements in Footwear, of which the following is a specification.

The present invention relates to footwear, and more particularly to the type which employs French or wooden heels having concave or undercut rear faces. An object of this invention is to provide for securing the rear upper portion of the heel 15 firmly to the shoe to prevent separation of the heel from the shoe at the rear of the heel. Another object of the invention is to provide fastening means which will not add materially to the cost of the shoe.

20 To these and other ends, the invention consists of certain parts and combinations of parts all of which will be hereinafter described, the novel features being pointed out in the appended claims.

25 In the drawings:

Figure 1 is a view of a shoe partially in section showing the invention applied thereto;

Fig. 2 is a view of the cup of the heel 30 showing the fastener applied thereto;

Fig. 3 is a perspective view of the fastener; and

Fig. 4 is a view of the heel seat of the shoe showing the openings in which the 35 prongs or projections are fitted.

A wooden or French heel shoe as now constructed has a counter 1 at the rear, with an inwardly or under turned portion to the upper side of which the inner sole 2 is secured, said sole usually having a reinforcement 3 at its heel portion formed of leather board or other material. The outer sole 4 is secured to the inner sole over the under turned edge 5 of the upper, and this outer 40 sole is trimmed or cut at its rear to provide a heel seat for engagement by the cup 6 of the heel 7. The rear face of the heel is undercut or concaved so that the rear edge of the top lift 8 lies considerably in advance 45 of the rear or heel portion of the upper.

Owing to the fact that the rear face of the heel is undercut or concaved, it has been customary to drive the screws and nails 9 or other fasteners through the inner and 50 outer soles into the heel at a point consider-

ably in advance of the upper rear edge of the heel, so as not to pass through the rear face of the heel. As a consequence the strain or stresses on the heel have caused the upper rear portion to separate from the 60 heel seat, thus providing a gap between the heel and its seat. This invention overcomes this objection by providing fastening means which ties the shoe heel to its seat at the extreme upper rear edge of the heel.

65 The fastener preferably comprises a plate or member having a body portion 10 secured to the cup of the heel in the rear of the fastener 9 by a screw or other fastening device 10a and provided preferably with two 70 rearwardly extending prongs or projections. Each of these projections may have a portion 11 extending at an obtuse angle to the body portion 10 and a body portion 12 extending substantially parallel to the body portion, 75 the projections preferably tapering toward their free ends which are spaced from the cup of the heel and lie substantially above the upper rear edge of the heel.

The shoe has openings for the reception 80 of the rearwardly extending projections, these openings being preferably made by a tool formed like the fastener and driven into the shoe in rear of the outer sole and through the under turned edge of the upper, the counter and the reinforcement of the inner sole, so that the ends of the projections will lie between the reinforcement and the inner sole and above the counter in close proximity to the inner rear face of the 90 shoe, thus providing a strong anchorage in the shoe.

85 In attaching the heel, the latter is first provided with the fastener and the shoe is provided with the openings. The prongs or 95 projections on the fastener are introduced into the openings. The heel and its seat having previously been provided with an adhesive, the heel is clamped on the heel seat of the shoe and is, when the adhesive has 100 been hardened, provided with the fasteners 9.

What we claim as our invention and desire to secure by Letters Patent is:

1. In a shoe having a heel seat and a heel 105 with a cup fitting said seat, a fastener secured to the cup of the heel and having a rearwardly extending prong projecting through the heel seat to be anchored in the shoe, said fastener having a form to permit 110

the prong to be inserted through the seat by a movement of the heel rearwardly with reference to such seat.

2. In a shoe having a heel seat and a heel 5 with a cup fitting said seat, a fastener secured to said cup and provided with two rearwardly extending prongs passing through the heel seat to be anchored in the shoe, said fastener having a form to permit the two prongs to be inserted simultaneously through the seat by a movement of the heel rearwardly with reference to such seat, the arrangement of the two prongs acting to prevent the rocking of the heel on 10 the seat.

3. In a shoe having a heel seat and a heel with a cup fitting said seat, a fastener having a body portion and two prongs extending rearwardly from the body portion through 20 the heel seat, each of said prongs having a portion at an obtuse angle to the body portion to facilitate the insertion of the prongs through previously formed openings in the seat, and a portion spaced from the cup and 25 lying substantially parallel with the body portion and a single fastener passing through said body portion into the heel to secure the fastener to the heel cup while permitting said fastener to turn slightly on said heel 30 in order that the heel may be shifted laterally relatively to the seat.

4. In a shoe having a counter with an inwardly turned portion and also having a heel provided with a cup for engaging the 35 heel seat of the shoe; a fastener secured to the cup and having a rearwardly turned prong engaging over the inwardly turned

portion of the counter at the rearmost portion of the latter.

5. In a shoe, a counter having an inwardly turned portion, an inner sole secured above said inwardly turned portion of the counter and provided with a reinforcement on the under side of its heel portion, a heel, and a fastener for the heel 45 overhanging a portion of the inwardly turned portion of the counter and passing through the reinforcement and between the latter and the inner sole.

6. A shoe provided with a counter formed 50 with an under turned edge, an inner sole secured above said under turned edge of the counter and provided with a reinforcement on its under side, a heel, and a fastener for securing the rear portion of the heel to the 55 shoe secured to the cup of the heel and provided with a rearwardly extending projection extending through the reinforcement and above the under turned portion of the counter between the reinforcement and the 60 inner sole.

7. In a shoe having a heel seat and a heel with a cup fitting said seat, a fastener having a body portion secured to the cup of the heel and two prongs extending in the same 65 direction from one edge of said body portion through the heel seat, each of said prongs having a portion spaced from the cup and lying substantially parallel with the body portion and to one side of the 70 latter.

GROVER C. HAUSER.
JOHN H. DOLAN.

It is hereby certified that in Letters Patent No. 1,261,524, granted April 2, 1918, upon the application of Grover C. Hauser and John H. Dolap, of Rochester, New York, for an improvement in "Footwear," an error appears in the printed specification requiring correction as follows: Page 1, line 74, strike out the word "body," second occurrence; and that the said Letters Patent should be read with this correction therein that the same may conform to the record of the case in the Patent Office.

Signed and sealed this 23d day of April, A. D., 1918.

[SEAL.]

F. W. B. CLAY,
Acting Commissioner of Patents.

Cl. 36--734.
